Primary Examiner — Darlington Ly

(57) CLAIM

The ornamental design for a camping box, as shown and described.

DESCRIPTION

FIG. 1 is a perspective view of a camping box embodying our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a perspective view thereof, with the trays pulled out.

The broken lines in the drawings illustrate portions of the camping box that form no part of the claimed design.

1 Claim, 6 Drawing Sheets
